UNITED STATES PATENT OFFICE.

JAMES J. PARIS, OF CHICAGO, ILLINOIS.

COLLAR-ATTACHING MEANS.

Application filed March 24, 1924. Serial No. 701,280.

To all whom it may concern:

Be it known that I, JAMES J. PARIS, a citizen of the United States, and a resident of the city of Chicago, in the county of Cook and State of Illinois, have invented 5 certain new and useful Improvements in a Collar-Attaching Means; and I hereby declare that the following is a full, clear, and exact description of the same, reference being had to the accompanying drawings, and 10 to the numerals of reference marked thereon, which form a part of this specification.

This invention relates to a collar attaching means and comprises an offset member on 15 the rear of the collar adapted for insertion in a suitable slit in the back of the neck band of the shirt for anchoring the collar thereto.

The invention consists of the novel structure and combinations hereinafter described 20 and more particularly pointed out and defined in the appended claim.

In the accompanying drawings which illustrate a preferred embodiment of this invention and in which similar reference numerals refer to similar features in the different views.

Figure 1 is a fragmentary elevational view 25 of a shirt with my improved collar attached thereto.

Figure 2 is a sectional view taken upon the line 2—2 of Figure 1.

Figure 3 is a rear elevational view of the 30 collar attached to a shirt with a part broken away.

Figure 4 is a fragmentary elevational view 35 of a shirt with the rear part of the neck band reversed.

Figure 5 is a fragmentary elevational view 40 of the interior of the neck band of a shirt showing a slightly modified form of the invention.

As shown on the drawings:

In referring to the drawings the reference 45 numeral 1 indicates the collar band on a shirt having a vertical slit 2 for receiving the offset tongue 3 on the collar 4. This offset tongue is preferably stamped or cut from the collar as shown in Figure 3.

50 In Figure 5 the offset tongue 5 is shown as integral with the lower margin of the collar and as provided with a slit 6 for attach-

ment to the shank of a collar button. This collar is therefor adapted to be attached to the band of the shirt by either the tongue 55 5 engaging through a suitable slit as shown in Figures 1 and 2 or by the usual collar button inserted in the slit 6.

In Figures 1 and 4 I have an improved construction whereby the usual front collar 60 button is eliminated. In these constructions a securing tape 7 is sewed to the inside of the shirt neck band at 7^a. To secure the collar in position said tape is engaged through the front collar button holes of the 65 shirt as shown in Fig. 4 and subsequently through the button holes in the front of the collar 4 as shown in Figure 1 and then laterally and upwardly through a securing 70 aperture or opening 8 in a usual collar flap 75 9, the free end of said tape 7 being engaged under said flap. Said securing tape 7 is preferably made in tubular form at 10 to facilitate the engagement thereof through the button holes.

It will accordingly be observed that this invention provides efficient means for securing a collar in proper position and at the same time eliminating the usual collar buttons both front and rear. The devices 80 provided are inexpensive, comfortable and may be easily adjusted.

I am aware that many changes may be made, and numerous details of construction 85 may be varied through a wide range without departing from the principles of this invention, and I therefore do not purpose limiting the patent granted hereon, otherwise than necessitated by the prior art.

I claim as my invention:

The combination with a shirt neckband, 90 of a collar having an aperture in one of its flaps, and a securing tape sewed to the inside of said neckband and formed tubular intermediate its length and flattened at its ends, said tubular portion adapted to engage through the front collar button holes of said neckband and then through the front button holes of the collar, the free flattened end of said tape adapted to engage said collar 95 flap aperture.

In testimony whereof I have hereunto subscribed my name.

JAMES J. PARIS.
